(57) **CLAIM**

The ornamental design for a non-pneumatic tourniquet device, as shown and described.

DESCRIPTION

This application is also related to U.S. Design patent application Ser. No. 29/317,784, filed on May 6, 2008, now U.S. Design Pat. No. D625,824, and U.S. Design patent application Ser. No. 29/346,791, filed on Nov. 5, 2009, now U.S. Design Pat. No. D642,275.

FIG. 1 is a perspective view of a non-pneumatic tourniquet device showing our new design;

FIG. 2 is a top view thereof, the bottom view being a mirror image;

FIG. 3 is a first side elevational view thereof; the second side or opposite side view being a mirror image;

FIG. 4 is a third side elevational view thereof;

FIG. 5 is a fourth side elevational view thereof;

FIG. 6 is a cross-sectional view thereof, taken along line 6-6 in FIG. 2.

FIG. 7 is a perspective view thereof, with the central element seen in FIG. 1 through FIG. 6 removed in order to depict the inner structure of the non-pneumatic tourniquet device;

FIG. 8 is a top view of the non-pneumatic tourniquet device of FIG. 7, the bottom view being a mirror image;

FIG. 9 is a first side view of the non-pneumatic tourniquet device of FIG. 7, the second side or opposite view being a mirror image;

FIG. 10 is a third side view of the non-pneumatic tourniquet device of FIG. 7;

FIG. 11 is a fourth side view of the non-pneumatic tourniquet device of FIG. 7; and,

FIG. 12 is a cross-sectional view of the non-pneumatic tourniquet device of FIG. 7, taken along line 12-12 of FIG. 8.
